UNITED STATES PATENT OFFICE.

WILLIAM H. ROBY, OF EAST CAMBRIDGE, ASSIGNOR TO BOSTON AND SANDWICH GLASS COMPANY, OF SANDWICH, MASSACHUSETTS.

DESIGN FOR A LAMP-FOUNTAIN.

SPECIFICATION forming part of Design No. 11,890, dated July 27, 1880.

Application filed June 21, 1880. Term of patent 7 years.

To all whom it may concern:

Be it known that I, WILLIAM H. ROBY, a citizen of the United States, residing at East Cambridge, in the county of Middlesex and State of Massachusetts, have invented or produced a new and original Design for Lamp-Fountains, of which the following is a specification, reference being had to the accompanying drawings, making part thereof.

10 Figure 1 is a top view, Fig. 2 a bottom view, Fig. 3 a side elevation, and Fig. 4 a transverse section, of a fountain formed externally in accordance with the said design, which is composed of a flat arched top, A, an inverted arched bottom, B, and two pyramidal frustums, C D, of eight sides each, joined to each 15 other at their larger bases, and at their smaller

ones to the arched top and bottom. Four of the sides of each frustum are larger than the remaining four, as shown. A tubular mouth, 20 E, projects up from the crown of the arched top, a notched stem, F, being projected down from that of the arched bottom.

What I claim as my invention is as follows, 25 viz:

The design, substantially as described, for a lamp-fountain, it consisting of the arched top and bottom and the two pyramidal frustums, all being as and arranged essentially as set forth.

WILLIAM H. ROBY.
